SCREEN FOR AUTOMOBILE WINDOWS

Clifford L. Oman, Dallas, Wis.

Application June 17, 1933, Serial No. 676,298

2 Claims. (Cl. 156—39)

This invention relates to screen apparatus particularly adapted for windows and doors of motor vehicles.

It is an object of my invention to provide a simplified and efficient roller screen mechanism which will cooperate with the adjustable panes or glazing of automobile windows and which may be quickly raised, lowered or adjusted as desired or disposed compactly out of sight in the upper portion of the door frame.

It is another object of the invention not only to provide efficient screening for automobiles, for the exclusion of insects, dirt, small stones and the like, but to moreover provide a ventilation curtain which gives privacy to the occupants of the car.

It is a further and more specific object to provide roller screen structure of the class described wherein provision is made for forming a tight joint between the lower edge of the adjustable screen and the window pane.

These and other objects and advantages of the invention will be more fully set forth in the following description made in connection with the accompanying drawing, in which like reference characters refer to similar parts throughout the several views, and in which:

Fig. 1 is a side elevation with some portions broken away showing an embodiment of my invention applied to a conventional automobile door;

Fig. 2 is a top plan view of the door;

Fig. 3 is a cross section on an enlarged scale taken substantially on the line 3—3 of Fig. 1;

Fig. 4 is a vertical section taken on the line 4—4 of Fig. 2, and

Fig. 5 is a detail cross sectional view on an enlarged scale showing a suitable stiffening rod construction for the free edge of the netting as well as a suitable flexible strip construction forming a seal between the screen and the adjustable window pane.

As shown in the drawing, my improved screen construction is applied to a conventional automobile door, indicated as an entirety by the letter D having the usual opening at the upper portion thereof wherein the vertically slidable window pane or glazing P is mounted. The vertical edges of the pane P work in conventional cushioning guides G constructed of felt or other compressible material, which guides are secured in the opposing vertical portions of the open frame. The upper bar 6 of the door frame is not of conventional type but is spaced from the outer bar 7 to afford a horizontal

chamber 8 for accommodating the roller 9 of my screen construction. A cover plate 10 as shown covers chamber 8 and may be secured by suitable means to the upper edge of the bar 6. Curtain roller 9 is of the torsional spring-actuated type and carries at one end the usual trunnion 9a which is journaled in a suitable depending bracket 11 which may be supported from the plate 10 at the upper edge of the door. An elongated coiled spring 12 is housed within the opposite end of roller 9 and has one of its ends secured to the roller while its outer end is secured to a square pin 13 which is non-rotatively seated in a suitable recess provided in one of the vertical posts of the door frame. Flexible netting 14 of fine mesh such as fine copper or bronze screening is attached and rolled on roller 9 and the longitudinal or vertical edges of this netting are preferably formed smoothly and are guided in the vertical grooves of suitable guide strips 15 mounted on the opposing sides of the vertical posts of the door frame forming a smooth joint therewith. It will be noticed that the guides 15 for the netting are disposed in spaced relation and inwardly of the guides for the window pane.

The lower transverse edge of netting 14 is secured to a tubular rod 16 which as shown is of rectangular cross section and has a slot along its top in which the netting is clamped and secured by means of an angle clip 17 extending longitudinally along the outer upper corner of the tubular rod 16. Elongated angle clip 17 also clamps or secures a flexible wiper strip 18 between its depending flange and the outer longitudinal side of the rod 16. Wiper strip 18 is preferably constructed of rubber or some other suitable material having requisite flexibility and elasticity and is provided with an outturned longitudinal wiper flange which is adapted to engage and seal against the inner surface of the window pane.

Within tubular rod 16 are slidably mounted a pair of retaining plungers 19 which carry cooperating depending finger members 19a at their inner and opposed ends and which as shown have depending arms 19b at their outer ends terminating in projections or detents 19c which are adapted to engage suitable vertical racks 20 secured in the channels of guides 15. As shown racks 20 comprise elongated strips provided with a series of spaced recesses or apertures for accommodating the detents 19c.

A compression spring 21 is interposed between the inner ends of the two plungers 19 normally

urging both plungers outwardly in extended position.

When not in use the entire sheet of netting 14 is wound about roller 9 and concealed within the horizontal compartment 8 formed in the upper portion of the door frame, the stiffening rod 16 and finger members 19a only being disposed below the top bar 6 of the door.

My screen may be very quickly and easily extended to operative position by pressing the finger grips together and thereby releasing the detents 19c from engagement with the retaining racks 20. The screen may cover the entire window opening if desired or may be readily set in various adjusted positions. It will also be noted that because of the wiper type joint or seal effected between the strip 18 and the window pane, that the screen may be extended to fully open position covering the entire window opening while the window pane may be partially closed. This is often desirable for privacy. The netting is preferably of such fine mesh that a person on the outside of the car cannot see the occupants therethrough unless the interior of the automobile is illuminated, although the driver and other occupants, being close to the netting, can readily see therethrough.

The function of my screen structure as a curtain can be appreciated when it is realized that today thousands of people travel in automobiles and many sleep therein and change their clothes.

From the foregoing description it will be seen that I have provided a simple and highly efficient roller screen mechanism specially adapted for windows and doors of a motor vehicle,

capable of being manufactured at relatively low cost and adapted to be easily installed in conventional automobile doors.

It will, of course, be understood that various changes may be made in the form, details, proportions and arrangement of the parts without departing from the scope of my invention, which, generally stated, consists in a device capable of carrying out the objects above set forth and in the novel parts and combinations of parts disclosed and defined in the appended claims.

What is claimed is:—

1. In a window frame having opposed parallel guides and a window comprising an unframed, rigid, transparent sheet slidable on said guides, a spring actuated roller screen mounted transversely at the ends of said guides, said screen having at its lower edge a stiffening rod, means for retaining said screen in various extended positions and a strip connected with said rod and extending longitudinally thereof and at an angle with respect to the plane of said screen for making wiping engagement with said window. 90

2. In a window frame having opposed parallel guides and a window slidable on said guides, a spring actuated roller screen mounted transversely at the ends of said guides, said screen having at its lower edge a stiffening rod, means for retaining said screen in various extended positions and a strip connected with said rod and extending longitudinally thereof and between said rod and said window for making wiping engagement with said window. 100

3. In a window frame having opposed parallel guides and a window slidable on said guides, a spring actuated roller screen mounted transversely at the ends of said guides, said screen having at its lower edge a stiffening rod, means for retaining said screen in various extended positions and a strip connected with said rod and extending longitudinally thereof and between said rod and said window for making wiping engagement with said window. 105
